UNITED STATES PATENT OFFICE

105,163

DESIGN FOR A ROBE

Ralph D. Cooper, New York, N. Y.

Application May 7, 1937, Serial No. 69,211

Term of patent 3½ years

To all whom it may concern:

Be it known that I, Ralph D. Cooper, a citizen of the United States of America, residing in Manhattan, county of New York, and State of New York, have invented a new, original, and ornamental Design for a Robe, of which the following is a specification, reference being had to the accompanying drawing, forming part thereof, wherein,

The novelty of my design resides in the embroidered features in combination with the entire garment as shown.

I claim:

The ornamental design for a robe, substantially as shown, and described.

RALPH D. COOPER
